US0D1025254S

(12) **United States Design Patent** (10) **Patent No.:** **US D1,025,254 S**
(45) **Date of Patent:** **** Apr. 30, 2024**

(54) **EXERCISE EQUIPMENT**

(71) Applicant: **Xiongwei Tao**, Zhejiang (CN)

(72) Inventor: **Xiongwei Tao**, Zhejiang (CN)

(**) Term: **15 Years**

(21) Appl. No.: **29/928,017**

(22) Filed: **Feb. 7, 2024**

Related U.S. Application Data

(63) Continuation of application No. 29/911,906, filed on Sep. 11, 2023.

(57) **CLAIM**

The ornamental design for an exercise equipment, as shown and described.

DESCRIPTION

FIG. 1 is a front, left, top perspective view of an exercise equipment, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures illustrate portions of the exercise equipment that form no part of the claimed design.

1 Claim, 8 Drawing Sheets
